SWITCH POINT CONNECTION

Beverly A. Lundy, Larchmont, N. Y., assignor to
 Railroad Accessories Corporation, New York,
 N. Y., a corporation of New York

Application September 14, 1934, Serial No. 743,978

3 Claims. (Cl. 246—253)

This invention relates to signalling, especially railway signalling, and more particularly to railway electric signalling.

Those familiar with the art of railway signalling know that there has always been a considerable difficulty in properly connecting a circuit controller, positioned at a track switch, with that track switch. This difficulty arises from the fact that the circuit controller, which is usually positioned upon a track tie adjacent the point of the switch, does not remain in the same alignment with the switch as when originally installed. This is due to the fact, as is well known, that not only do the rails move longitudinally, as a whole, but each rail does not have the same amount of forward or backward movement. Furthermore, the angular relation between the tie upon which the circuit controller is secured and the rails does not remain as originally set. The switch point, furthermore, also has substantially a longitudinal movement which may be independent of that of the adjacent track rails. The switch point also sometimes has a tendency to roll about its axis. Added to all of the above mentioned likely changes, there is also the change which is occasioned by the normal wear of the gauge side of the thread of the rail and both sides of the switch point. The effect of all these changes is to not only bring undue strains upon the connections between the switch point and the circuit controller, but also prevent that close adjustment which is necessary to insure the proper and desired control of the signal circuits by the circuit controller. That this difficulty is a serious one, may be readily realized when it is known that the modern circuit controller attached to a switch point is relied upon to open the signalling circuits governing traffic over that switch when the normally closed switch point is opened by an amount not exceeding three sixteenths of an inch. To secure such a close adjustment in structures so large and so rough and subjected to so many conditions causing them to shift is easily realized to be a difficult task.

A principal object of applicant's invention is to provide a means for interconnecting a railway switch point with a railway switch circuit controller, sometimes known as a track switch box in such a way that the ordinary shifting of the various structures effective upon the connection, will not cause an undue strain thereon.

A further object of applicant's invention is to provide a connection of the type described which will be so constructed that practically a universal

joint will exist at two places between a track switch and a switch circuit controller.

Another object of the applicant's invention is to provide a novel form of universal joint which is not only sturdy and flexible in operation but also offers notable improvements from the standpoint of economy in manufacture and ease of replacement.

Other objects and advantages will appear as the description of the particular physical embodiment selected to illustrate the invention progresses, and the novel features will be particularly pointed out in the appended claims.

In describing the invention in detail and the particular physical embodiments selected to illustrate the invention, reference will be had to the accompanying drawing and the several views thereon, in which like characters of reference designate like parts throughout the several views, and in which:

Figure 1 is a top plan fragmentary view of a railway switch, its supporting ties, a switch circuit controller and connecting means between the circuit controller and track switch constructed in accordance with applicant's invention; Fig. 2 is a fragmentary side elevational view of the arrangements as shown by Fig. 1, the rail being shown in section; Fig. 3 is a view in longitudinal section of one of the socket devices shown by Fig. 2, on the plane indicated by the line III—III of Fig. 2, viewed in the direction of the arrows at the ends of the line; Fig. 4 is a similar sectional view of the other socket device shown by Fig. 2, on the plane indicated by the line IV—IV of Fig. 2, viewed in the direction of the arrows at the ends of the line; Fig. 5 is a fragmentary detail view in side elevation, partly in section, and on a larger scale, of the connecting socket for the switch point lug; Fig. 6 is a cross-sectional view on the plane indicated by the line VI—VI of Fig. 5, viewed in the direction of the arrows at the ends of the line.

In Fig. 1, numeral 1 designates an ordinary railway track tie. This track tie supports the rail 2 which has a switch point 3 operating in conjunction therewith.

The tie 1 also supports an ordinary and well known switch circuit controller 4 sometimes known as a track switch box. This circuit controller is illustrated as of the usual type and has a protruding operating shaft 5 bearing an operating crank arm 6.

The problem confronting applicant was to connect the operating crank arm 6 with the switch point 3 in such a manner that the ordinary shift-

55

ing and movement of the various parts would not cause an undue strain upon the connection between operating crank arm 6 and switch point 3 and would at the same time allow an adjustment of the electrical contacts within the switch box 4 such that a departure of the switch point 3 from the rail 2 of more than three sixteenths of an inch would cause the signalling circuits controlling traffic over the switch to be opened or closed or put in other condition necessary to properly control traffic.

By applicant's method of connection, a switch point lug 7 is fastened by any suitable and appropriate means to the switch point 3.

15. The lug illustrated is formed of round bar stock, straight throughout its length, and may have, as shown, a plate 8 welded thereto, of suitable contour to permit the unitary lug structure thus constituted to be readily attached to the switch point, as by bolts 9. The outer, free end 10 of the lug is threaded to receive a nut 11.

20. Fitted in the outer end of the operating crank arm 6 of the switch box 4 applicant provides a bolt 12 having a shoulder 13 bearing against the crank arm head 14 within which the bolt is fastened in a suitable manner. The bolt is provided at its outer threaded end with a retaining nut 18.

25. In order to connect the free lug end 10 with the free bolt end 18, applicant makes use of a connecting rod or pipe 20 having on each end thereof a socket of applicant's construction.

30. The socket 21 connecting with bolt 12 is best shown in Fig. 3. This socket is formed with a fixed concave spherical surface 22 which faces that portion 23 of the bolt which lies within the socket. Opposite the concave surface 22 is a plunger or movable member 24, formed with a concave spherical surface 25. The plunger 24 fits loosely into the cylindrical portion 26 of the socket 21 and has a tail member 27 encircled by a spring 28, one end of which enters and bears against the mushroom-like head of the plunger 24, and the other end of which bears against a suitable abutment. In the present case the abutment against which the spring 28 bears is a cap 29 screw threaded into the cylinder 26.

35. Interposed between the bolt portion 23 and the fixed concave bearing surface 22 and movable concave bearing surface 25, I have provided, in pursuance of my invention, a pair of contact elements 30, preferably identical in function and in form, and which are therefore identified by the same reference character 30 wherever they appear throughout the system illustrated.

40. Each of these contact elements, in the now preferred forms selected for illustration, comprises a lozenge shaped member having a cylindrical body with one face 31 of convex contour, and thus adapted to cooperate with the contiguous concave face of the fixed bearing surface 22 or of the movable bearing surface 25, as the case may be, all of the surfaces being preferably spherical, but not necessarily of the same radius. In fact I prefer to have the convex surfaces 31 of somewhat shorter radius than the concave surfaces 22 and 25, whereby the universal joint effect between the connector 20 and bolt 14 is favored.

45. The rear face 32 of each of the contact elements 30 is preferably adapted to be seated firmly against the contiguous free portion 23 of the bolt 14, and will therefore desirably be of suitable shape to conform therewith. For this

purpose the rear face 32 of each of the pair of contact elements in Fig. 3 is of arcuate concave shape and fits snugly against the cylindrical periphery of the bolt, as shown clearly in Fig. 5, to be described more at length hereinafter. The 5 pairs of contact elements 30 just described act therefore, as, the "ball" member of the joint formed in each socket with the fixed and movable concave bearing surfaces. This form of joint permits a desirable range of relative angular displacement between the bolt socket 21 and the cooperating bolt of the switch box crank, which should be, and is rigidly supported by the crank arm 6.

50. The socket member 21 has a screw threaded 15 orifice 33 into which may be screwed the pipe or rod 20 for connection to the socket.

At the switch point end of the connection the free end 10 of the lug 7 extends through orifices 34 in a cylindrical portion 35 of a V-shaped 20 socket designated as a whole by 36. Within the socket the free end portion 37 of the switch point lug is contacted as at 38, by the concave arcuate bases of lozenge shaped contact elements 30 which may be identical in shape with those 25 already described, having convex faces 31 which are preferably spherical and of slightly shorter radius than the radius of the concave bearing surfaces with which they cooperate respectively, to facilitate an easy universal movement relatively thereto.

55. The socket member 36 is formed at one end with an inner spherical concave surface 39. Directly opposite the concave surface 39 a plunger 40, having a concave bearing surface 25, 35 just like the plunger 24, bears against the face 31 of the cooperating contact element. In the same way as when spring 28 bears against plunger 24, a spring 41 bears against plunger 40 and abuts against a screw threaded cap 42. The 40 socket member 36 is also provided with a portion at an angle to the axis of the plunger 40. This portion is designated 43, and is best shown in Fig. 2, and its interior as shown in Fig. 5, is formed with a screw threaded orifice 44 into 45 which a bent end 45 of the pipe or rod 20 may be screwed. By this angle portion applicant provides a socket which greatly facilitates the proper placing of the pipe or rod 20 so that it will nicely clear the bottom of the rail 2.

60. The construction hereinbefore described is obviously one such that practically a universal joint is provided at both the switch point and the switch box operating crank arm so that movements back and forth and shifting of the various parts will bring practically no strain upon the connections.

Applicant's connection is also such that very close adjustment of the switch box or switch circuit controller 4 may be made, because if wear 60 takes place between the contact elements 30 and the contiguous concave bearing surfaces, the parts are still tightly held together by the springs 28 and 41, so that even if the connections have worn, the adjustment of the switch may be made 65 just as though they had never worn.

65. By the provision of the separately formed contact elements 30 above described, I have made a notable improvement over the structure used conventionally in the formation of universal 70 joints in these track switch box connections. Usually the switch point lug, and the switch box bolt, are made with a spherical head on their respective outer ends, and this head has been formed either integrally, or on a separable part 75

consisting of a short rod, but in any event the fabrication of these spherical heads is attended with considerable difficulty from a manufacturing standpoint, if they are made with desirable 5 accuracy.

It will be understood readily by those skilled in the art that the contact elements 30 can be easily and accurately made very cheaply and to very exact dimensions and that accordingly 10 they offer desirable advantages both in manufacture and for ease of replacement. Their provision permits the use of a switch point lug 1 and bolt 12 each of which is straight throughout and which therefore has a slip fit within the 15 embracing contact elements 30, to accommodate changes in length of the lug and/or of the bolt due to variations of temperature or creeping.

Although applicant has illustrated and described a particular physical embodiment of his 20 invention, and has explained the construction, principle, and mode of operation thereof, nevertheless, he desired to have it understood that the form selected is merely illustrative but does not exhaust the possible physical embodiments of 25 the idea of means underlying the invention.

What I claim as new and desire to secure by Letters Patent of the United States, is:

1. In a railway track switch box connection, in combination: a lug member adapted for connection with a track switch point, a bolt member adapted to be connected with the crank arm of a track switch box, said switch point lug and said bolt each having a free end, a connecting rod having at one end a socket adapted to embrace 30 and be connected with the free end of said switch point lug, and having at its other end a socket adapted to embrace and be connected with the free end of said bolt; each of said sockets being formed with a fixed bearing surface and each 35 having a movable member formed with a bearing surface presented in opposed relation to said fixed bearing surface, said bearing surfaces in each socket being adapted to be positioned on opposite sides of the free end of that member 40 of the track switch box connection respectively to be connected with said socket; and a pair of contact elements in each socket, said elements in each socket being interposed respectively between said free end thereby embraced and the corresponding 45 fixed and movable bearing surfaces of said socket; and means included in each socket, to hold said contact elements in contiguous operative relation with said bearing surfaces and with the free end of the member thereby 50 embraced, each of said free ends being capable of longitudinal movements in use, relatively to its contiguous contact elements, and each socket being capable of universal movement relatively to the free end embraced by it, without disturbing 55 the snug assembly of said parts.

2. In a railway track switch box connection, in combination: a lug member adapted for connection with a track switch point, a bolt member adapted to be connected with the crank arm of a track switch box, said switch point lug and 60

said bolt each having a free end, and a connecting rod having at one end a socket adapted to embrace and be connected to the free end of said switch point lug and having at its other end a socket adapted to embrace and be connected 5 with the free end of said bolt; each of said sockets being formed with a fixed concave bearing surface and each having a plunger member formed with a concave bearing surface presented in opposed relation to said fixed concave bearing surface, said concave bearing surfaces in each socket being adapted to be positioned on opposite sides of the free end of that member of the track switch box connection respectively to be connected with said socket, and a pair of contact 10 elements in each socket, said elements in each socket being interposed respectively between said free end thereby embraced and the corresponding fixed and movable bearing concave surfaces of said socket; and means, comprising a coiled 20 spring and an abutment therefor included in each socket, to hold said contact elements respectively in contiguous operative relation with said concave bearing surfaces and with the free end of the member thereby embraced, and said contact ele- 25 ments having each a convex bearing surface to cooperate with the contiguous concave bearing surface, each of said free ends being capable of longitudinal movements in use, relatively to its contiguous contact elements, and each socket 30 being capable of universal movement relatively to the free end embraced by it, without disturbing the snug assembly of said parts.

3. A connector member for a railway track switch box connection of the class comprising a switch point lug, a switch box bolt and a connector member with end sockets adapted to embrace and be connected with the free ends of said bolt and of said lug respectively; said connector member being characterized by having each of said sockets formed with a fixed concave bearing surface and with a plunger member formed with a concave bearing surface presented in opposed relation to said fixed concave bearing surface, said concave bearing surfaces in each socket being adapted to be positioned on opposite sides of the free end of the bolt or of the lug respectively; and a pair of contact elements in each socket interposed respectively between said bolt or lug and the corresponding fixed and movable bearing concave surfaces of said socket; and a coiled spring and an abutment therefor included in each socket, to hold said contact elements in contiguous operative relation with said bearing surfaces and with the bolt or lug thereby embraced, said contact elements having each a convex bearing surface to cooperate with a contiguous concave bearing surface, and having each a base fitted to the bolt or lug, each of said free ends being capable 55 of longitudinal movements in use, relatively to its contiguous contact elements, and each socket being capable of universal movement relatively to the free end embraced by it, without disturbing the snug assembly of said parts.

BEVERLY A. LUNDY. 65
